(57) **CLAIM**

The ornamental design for a fillable dog toy, as shown and described.

DESCRIPTION

FIG. 1 is a top plan view of my new design for a fillable dog toy.

FIG. 2 is a bottom plan view of FIG. 1.

FIG. 3 is a left side elevation view of FIG. 2, the right side elevation is a minor images of the left side.

FIG. 4 is a front side elevation view of FIG. 2.

FIG. 5 is a rear side elevation view of FIG. 2.

FIG. 6 is a top perspective view of FIG. 2.

FIG. 7 is a top perspective view of FIG. 2 with the bottle removed.

FIG. 8 is a top plan view of an alternate embodiment of my new design for a fillable dog toy.

FIG. 9 is a bottom plan view of FIG. 8.

FIG. 10 is a left side elevation view of FIG. 9, the right side elevation is a minor images of the left side.

FIG. 11 is a front side elevation view of FIG. 9.

FIG. 12 is a rear side elevation view of FIG. 9.

FIG. 13 is a top perspective view of FIG. 9.

FIG. 14 is a top perspective view of FIG. 9 with the bottle removed.

FIG. 15 is a top plan view of an alternate embodiment of my new design for a fillable dog toy.

FIG. 16 is a bottom plan view of FIG. 15.

FIG. 17 is a left side elevation view of FIG. 16, the right side elevation is a minor images of the left side.

FIG. 18 is a front side elevation view of FIG. 16.

FIG. 19 is a rear side elevation view of FIG. 16.

FIG. 20 is a top perspective view of FIG. 16; and,

FIG. 21 is a top perspective view of FIG. 16 with the bottle removed.

The dot-dash-dot broken lines in FIGS. 3, 5, 10, 12, 17 and 19 are for illustration of a bottle only and form no part of the claimed design. The evenly spaced broken lines represent stitching.
